FUEL CONTROL

Stanley G. Best, Manchester, Conn., assignor to United Aircraft Corporation, East Hartford, Conn., a corporation of Delaware

Filed Dec. 21, 1954, Ser. No. 476,715

4 Claims. (Cl. 170—135.74)

This invention relates to controls for turbine type power plants and more particularly to combined propeller pitch and fuel controls for turboprop power plants.

It is an object of this invention to provide a control which compensates for the response time lag between propeller pitch change and fuel flow change during transient conditions.

It is a further object of this invention to provide a control of the type described which incorporates a droop type fuel control with a reset mechanism for the scheduled fuel flow so that the desired fuel flow is always achieved for steady-state conditions while permitting the propeller control and fuel control to be separate and avoiding the necessity of the two controls tracking each other.

These and other objects of this invention will become readily apparent from the following detail description of the drawing which is a schematic illustration with some of the parts in cross section.

My copending patent application Serial No. 476,716, filed by Stanley G. Best, December 21, 1954, now Patent 2,829,722, discloses a turboprop control system which utilizes a common r.p.m. sensing device for both the fuel control and the propeller pitch control to avoid tracking errors between the two controls. This fuel control system has similar dynamic properties as the one disclosed in the above-referred to application, however, a droop type fuel control is utilized with a resetting mechanism such that it is not necessary to have the propeller pitch control and the fuel control track each other.

Referring to the drawing, a turboprop power plant combination is generally indicated at 10 and includes a compressor section 12, a combustion section 14 and a turbine and exhaust section 16. As is usual, at least a portion of the turbine section drives a variable pitch propeller 18. The propeller 18 has the pitch of its blades regulated by a control schematically illustrated at 20. The propeller control and the pitch changing mechanism may be of the type shown and described in Caldwell et al. Patent No. 2,174,717 or Martin Patent No. 2,361,954.

A single power lever 30 is operatively connected to a group of coordinating cams for both the propeller and fuel controls. The power lever is adapted to rotate a governor setting cam 32, a fuel flow scheduling cam 34 and a propeller governor setting cam 36. The cam 36, of course, will normally adjust a speeder spring of a governor which in turn regulates the pitch of the blades of the propeller 18.

The cam 32 operates the rack 40 which by means of pinions 42 and 44 drives a rack 46 through a pulley and cable arrangement 48 and 50. The rack 46 sets a speeder spring 52 which opposes the centrifugal force provided by flyweights 54 which may be rotated in proportion to the speed of rotation of the power plant by any suitable well known means. The spring 52 and the flyweights 54 comprise a governor for operating an r.p.m. pilot valve generally indicated at 56. The governing mechanism moves the valve stem 58 and the

lands 60 and 62 so as to conduct high pressure fluid or drain pressure to the chamber 66 of an r.p.m. servo device generally indicated at 68. The r.p.m. servo has a piston 70 portions of which are of different areas. High pressure fluid is continuously supplied to the chamber 72 so that when high pressure fluid is conducted to chamber 66 the piston 70 moves downwardly, while if drain pressure is supplied to the chamber 66 the piston 70 is moved upwardly. Thus it will be seen that the fuel 10 droop governor, in response to either a power lever movement or a speed change, positions the r.p.m. servo 68 via the r.p.m. pilot valve 56 which in turn moves the rod 76 and varies the opening of the fuel valve 78 in a manner to be described hereinafter. The r.p.m. servo piston via the rod 76 and beam 80 also moves a follow-up sleeve 82 which surrounds the lands 60, 62 of the r.p.m. pilot valve 56. As a result the position of the r.p.m. servo piston 70 always essentially corresponds to that of the pilot valve stem 58, including the lands 60 and 62. This provides the desired fuel flow droop.

Fuel flow droop can be described as a deviation of the final fuel flow value from the desired (set) fuel flow over the full operating range. Thus, when an off condition occurs, the fuel flow does not eventually return to the exact same set condition. This slight error or deviation provides a certain amount of stability to the control. The output of the r.p.m. servo 68, namely the motion imparted to rod 76, also moves a reset pilot valve 86 via the arm 88. In addition, the power lever can 30 also move the reset pilot valve via the cam 34 and the rod 90. The reset pilot valve 86 includes a land 94 which can pass high pressure fluid or fluid under drain pressure via the line 96 to the chamber 98 of a reset servo 100. The reset pilot valve meters fluid into or out 35 of the chamber 98 of the reset servo 100 so that it moves at a rate proportional to the reset pilot valve displacement. A restriction 102 may be provided in the line 96 so that the reset servo has a relatively slow response. With the reset servo 100 having a slow response and the 40 r.p.m. servo 68 having a relatively rapid response the control reacts such that during dynamic transients the action is similar to that of a permanent droop governor control, giving good stability and high rate of response, the reset being sufficiently gradual to have little effect on response.

45 The reset servo 100 by means of a reset spring 102 adds or subtracts spring force to the droop governor thus changing its setting. This change in setting in turn causes the stem 58 of the r.p.m. pilot valve 56 to move thereby 50 in turn causing motion of the piston 70 of the r.p.m. servo 68 until it has in turn recentered the land 94 of the reset pilot valve 86. The reset pilot valve being an integrating type of device will always return to its centered position insuring that the steady-rate fuel flow is 55 always that value which has been scheduled by the setting of the cam 34 and rod 90.

The action of the speed responsive mechanism is first to correct fuel flow in a direction to correct for an "off speed" condition and then to begin to reset itself in a direction to restore the fuel valve in its original position 60 regardless of speed change. The propeller governor is finally relied upon to bring the engine back to "on speed." The reset action is in a sense to restore the original fuel valve position and is a floating action which can only reach a null when the end of link 88 is in such 65 a position so as to close the pilot 86, and this position is fixed relative to the position of the fuel valve for any given compressor inlet pressure.

The action of the r.p.m. servo 68 on the throttle valve 78 is modified by the motion of a bellows 110 and rod 112. The bellows 110 is sealed and the outside thereof is exposed to compressor inlet pressure and temperature

such that the bellows responds to both inlet pressure and temperature. Motion of the free end of the bellows 110 and rod 112 positions a roller 114 which is interposed between the throttle valve stem 116 and a lever 118 which is engaged by the rod 76. The lever 118 is pivoted at 120.

The pump feeding fuel to the throttle valve normally would have the outlet pressure thereof maintained constant; or, the pressure drop across the throttle valve may be maintained constant by means of a by-pass type regulator 130 so that for any given position of the throttle valve a predetermined fuel flow will be obtained. These are well-known expedients in the art.

With a fuel control system of the type described, control functions of the following nature are obtained.

During transient conditions fuel flow is altered from the equilibrium or steady state value in a manner to aid in rapidly bringing the engine to the selected speed in a well damped manner, while equilibrium or steady state fuel flow is accurately defined, independent of any tracking errors between fuel and propeller control settings.

As a result of this invention it is readily apparent that a relatively simple yet highly accurate but dynamically stable control is provided.

Although only one embodiment of this invention has been illustrated and described herein, it will be apparent that various changes and modifications may be made in the construction and arrangement of the various parts without departing from the scope of this novel concept.

What it is desired to obtain by Letters Patent is:

1. In a fuel control for a turbine type power plant, a source of fuel under pressure, means for regulating the flow of fuel from said source to the power plant, manual means for setting said means for regulating the flow of fuel to maintain a desired fuel flow rate, a speed governor responsive to the speed of the power plant, means for setting said governor including an adjustable spring, a pilot valve biased in one direction by said spring and in the other direction by centrifugal force, a servo device controlled by said pilot valve and operatively connected to said fuel regulating means for temporarily varying fuel flow upon a change in power plant speed from the set speed, mechanism responsive to the relative position of said servo device and said manual means for resetting said governor including a second adjustable spring biasing said pilot valve in opposition to said first-mentioned spring said mechanism returning said fuel flow regulating means to its original position, and means responsive to at least one parameter of power plant operation for further varying fuel flow.

2. In a turboprop power plant including a propeller having variable pitch blades, means for regulating the pitch of said blades to increase the load on the engine with an increase in speed and to decrease the load on the engine with a decrease in speed, a droop fuel governor, a fuel flow scheduling member, power control means for controlling said pitch regulating means and setting said governor and said fuel flow scheduling member, said governor including a pilot valve, a fuel control valve for regulating the flow of fuel to the power plant, a servo device controlled by said pilot valve for varying the position of said fuel valve with variations in speed, a follow-up sleeve surrounding said pilot valve and operatively connected to said servo device to vary the effect of said pilot valve on said servo device, means for resetting said governor including a second servo device, a reset pilot valve for controlling said second servo device including operative connections to said first servo

device and said fuel flow scheduling member for comparing the relative positions thereof to return said fuel control valve to its original set position after a transient speed change, and means responsive to at least one parameter of power plant operation for further regulating the flow of fuel by said fuel control valve.

3. A turbine type power plant including a combustion chamber, a turbine driven by the gases from said combustion chamber, a compressor driven by the turbine, a variable pitch propeller driven by the power plant, means for varying the pitch of the propeller to control the speed of rotation thereof, a source of fuel under pressure, means for regulating the flow of fuel from said source to said combustion chamber, power control means for manually setting a schedule of fuel flow and operatively connected to said regulating means, a speed governor including a pilot valve, means for setting the speed of said governor in accordance with the setting of said power control means, a first servo device controlled by said pilot valve for changing the fuel flow regulated by said fuel regulating means when said speed governor calls for a fuel flow different than that called for by said power control means, a follow-up sleeve for said pilot valve, follow-up means mechanically connecting said first servo device and said sleeve, a reset servo device connected to said power control means and said first servo for resetting said governor to eventually return said fuel regulating means to the original fuel flow scheduled by said power control means including a reset pilot valve for sensing the relative positions of said first servo device and said power control means.

4. A power plant including a combustion chamber, a variable load for said power plant, means for controlling the speed of the power plant during variations in load, a source of fuel under pressure, means for regulating the flow of fuel from said source to said combustion chamber, power control means for setting a schedule of fuel flow and operatively connected to said regulating means, a speed governor driven by the engine, means for setting the speed of said governor in accordance with the setting of said power control means, a first servo device controlled by said governor for changing the fuel flow regulated by said fuel regulating means when said speed governor is in an off-speed condition calling for a fuel flow different than that called for by said power control means, follow-up means mechanically connecting said first servo device and said governor, and a reset servo device connected to said power control means and said first servo device for comparing the relative positions of said control means and first servo for resetting said governor to eventually return said fuel regulating means to the original fuel flow scheduled by said power control means, said means for controlling the speed of said power plant being effective to eventually return the power plant to the set speed when an off speed occurs.
